VENETIAN BLIND

Filed Dec. 28, 1945

UNITED STATES PATENT OFFICE

2,570,199

VENETIAN BLIND

James R. Brown, Houston, Tex.

Application December 28, 1945, Serial No. 637,554

3 Claims. (Cl. 160—119)

1

This invention relates to an improved Venetian blind.

A primary object of this invention is the provision of an improved Venetian blind characterized by two sections, either of which may be raised or lowered independently of the other, or the slats of which may be individually varied as desired, in such manner that the lower blind may be closed, while the upper is retained open for air and ventilation, or vice versa, as may be desired.

An additional object of the invention is the provision of such a device whereby the means for closing and lowering the upper and lower sets of slats, respectively, are located at a convenient point adjacent the center of the device, the arrangement being such as to obviate the necessity of fumbling with a plurality of cords located at a common point when such operation is desired.

Still another object of the invention is the provision of such a device wherein the operating cords thereof extend through slotted apertures in the ends of the slats, whereby the slats may be individually removed completely from the device for cleaning or painting, replacement or other purposes as may be desired.

Other objects reside in the combinations of elements, arrangements of parts, and features of construction, all as will be more fully pointed out hereinafter and disclosed in the accompanying drawings, wherein there is shown a preferred embodiment of this inventive concept.

In the drawings:

Figure 1 is a front plan view of one form of blind construction embodying features of this invention.

Figure 2 is a sectional view on an enlarged scale taken substantially along the line 2—2 of Figure 1, as viewed in the direction indicated by the arrows.

Figure 3 is an enlarged sectional view taken substantially along the line 3—3 of Figure 1, as viewed in the direction indicated by the arrows.

Figure 4 is a sectional view taken substantially along the line 4—4 of Figure 1, as viewed in the direction indicated by the arrows.

Figure 5 is an enlarged sectional view taken substantially along the line 5—5 of Figure 1, as viewed in the direction indicated by the arrows.

With continued reference to the drawing, the improved Venetian blind assembly, as shown in elevation in Figure 1, comprises an upper portion 17 and a lower portion 18 each of which covers substantially one-half of a window opening.

Each portion is separately adjustable both as to the angular position of its slats and the extent of the window opening covered thereby, and each portion or section of the blind has its own individual adjusting means.

The lower portion 18 has an upper terminal slat mounted on fixed supports near the vertical center of the window opening and a lower terminal slat, and intermediate slats which may be raised and lowered relative to the upper terminal slat to vary the extent of the window opening covered by the lower section 18 while the upper blind section 17 has a lower terminal slat mounted on fixed supports near the vertical center of the window opening, spaced from and substantially parallel to the upper terminal slat of the lower portion 18, and an upper terminal slat and intermediate slats which may be raised and lowered relative to the lower terminal slat to vary the extent of the upper portion of the window opening covered by the upper blind section 17.

The upper blind section 17 has means operative to guide the slats and hold them in proper operative position relative to the window opening and similar guide means may be provided for the lower section 18, if desired. The two terminal slats near the vertical center of the window opening are preferably covered on both sides by a pair of spaced-apart, substantially parallel cover plates extending transversely of the window opening at the mid-height location thereof.

In order to provide a closer fit of the blind with the window opening the blind sections 17 and 18 are preferably mounted in a common rectangular frame, generally indicated at 10, which closely fits the window opening and surrounds the blind sections, but this frame may be omitted, if desired, and the upper and lower sections of the blind mounted directly in the window opening.

In the illustrated embodiment, the frame 10 includes a hollow cornice or canopy 11 having depending end walls 12 and side walls 13, and side plates 14 respectively secured at their upper ends to the end walls of the cornice and at their bottom ends to the corresponding ends of a base sill or plate 15.

Where the frame 10 is used, the cover plates 16 are secured at their ends to corresponding edges of the vertical side plates of the frame in position to overlie the terminal slats of the two blind sections located near the mid-height portion of the frame. Each of the blind sections has a pair of terminal slats between which is a plurality of intermediate slats 19, each having a recess

20 in each end thereof. The slats of each section are connected together by the conventional web ladders 21 which hold the slats in properly spaced, parallel position when the blind sections are extended.

The lower terminal slat 19a of the upper blind section 17 is pivotally secured at its ends to the frame side plates 14 by a suitable mounting means such as pivot pins one of which is indicated at 22. A knob 23 is positioned substantially adjacent the closure member 16 at approximately the mid-point of the frame and operatively connected to the terminal slat 19a so that rotation thereof will turn the terminal slat about the axis of the mounting pins to change the angular relationship of all the slats in the section by relatively moving the opposite sides of the tapes 21 in the conventional manner.

Guide cords 24 connected at their lower ends to terminal slat 19a extend through the recesses 20 in the ends of the slats and over pulleys 25 within the cornice 11 to a common juncture with a tension spring 26 centrally positioned above the uppermost slat. These guide cords, being constantly under tension, serve to maintain the slats of the upper blind section in operative position in the upper portion of the window opening or frame 10.

A pair of lifting cords 30 extend over pulleys 31 also suspended in the cornice 11, one at each end thereof, and are attached at their ends to the opposite end portions of the movable upper terminal slat 19c of the upper blind section. The cords 30 are effective to raise and lower the upper terminal slat and the intermediate slats relative to the lower terminal slat 19a.

Obviously, a pull on the extremities of the elevating cords will raise the blind in the conventional manner, while adjustment of the knob 23 will vary the position of the slats. The upper terminal slat 19b of the lower blind section 18 is pivotally secured at its ends to the frame side plates 14 by suitable mounting means, such as pivot pins 22a. A knob 23a is positioned adjacent the closure member 16 at approximately the mid-point of the frame and operatively connected to the upper terminal slat 19b, so that rotation thereof will turn the terminal slat about the axis of the mounting pins 22a to change the angular relationship of all the slats in the lower blind section by relatively moving the opposite sides of the tapes in the conventional manner.

The lower section 18 is raised and lowered by a pair of lifting cords 33 which extend over pulleys 32 suspended below the lower terminal slat 19 of the upper section 17 between the cover plates 16. The cords 33 each extend downwardly from the respective pulleys 32 through the end recesses 20 in the intermediate slats of the lower section 18 and are connected at their lower ends, one to each end portion of the lower terminal slat 19d of the lower section 18. With the above-described arrangement, the pair of cover plates 16 constitute, in effect, a second cornice or canopy disposed below the cornice 11 and concealing the pulleys 32 and any mechanism connecting the knob 23a with the upper terminal slat 19b, as well as the two adjacent pivotally mounted terminal slats of the two blind sections.

The lowermost slat 19d of the section 18 is provided at its extremities with pins 35 adapted when the blind is in lowered position to be engaged by hooks 36 secured in any desired manner, as by pins or nails 37, to the base 15, thus insuring that when the blind is in lowered position

it will be securely held in such position regardless of any disturbance occasioned by wind or the like.

From the foregoing it will now be seen that there is herein provided an improved Venetian blind structure characterized by versatility and adaptability of adjustment and including two sections which may be independently raised or lowered, or wherein the slats may be readily adjusted. It will also be seen that by virtue of the slotted apertures 20 at the ends of the slats, any individual slat may be readily disassociated from its associated tape 21 and removed from the device for cleaning, painting or other purpose.

It will also be seen that there is herein provided an improved Venetian blind structure which accomplishes all the objects of this invention, and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

1. A Venetian blind assembly comprising a rectangular frame adapted to fit into a window opening, an upper and a lower blind section disposed in said frame respectively above and below the mid-height location of the latter and effective when extended to completely cover the area within said frame, each of said sections having an upper and a lower terminal slat, a plurality of intermediate slats disposed between said terminal slats and web ladders extending between said terminal slats and engaging said intermediate slats to hold said slats in operative assembly and tilt the intermediate slats upon tilting of the terminal slats when the blinds are extended, means pivotally connecting the lower terminal slat of said upper section and the upper terminal slat of said lower section to said frame with said lower and upper terminal slats extending transversely of the frame at the mid-height location of the latter and adjacent to each other, a plate extending transversely of the frame at the mid-height location thereof and covering the edges of the pivotally mounted terminal slats, and lifting cords supported on said frame at the upper end and at the mid-height location thereof and respectively connected to the upper terminal slat of said upper section and to the lower terminal slat of said lower section for independently raising and lowering said sections.

2. A Venetian blind assembly comprising a rectangular frame adapted to fit into a window opening, an upper and a lower blind section disposed in said frame respectively above and below the mid-height location of the latter and effective when extended to completely cover the area within said frame, each of said sections having an upper and a lower terminal slat, a plurality of intermediate slats disposed between said terminal slats and web ladders extending between said terminal slats and engaging said intermediate slats to hold said slats in operative assembly and tilt the intermediate slats upon tilting of the terminal slats when the blinds are extended, means pivotally connecting the lower terminal slat of said upper section and the upper terminal slat of said lower section to said frame with said lower and upper terminal slats extending transversely of the frame at the mid-

height location of the latter and adjacent to each other, a plate extending transversely of the frame at the mid-height location thereof and covering the edges of the pivotally mounted terminal slats, lifting cords supported on said frame at the upper end and at the mid-height location thereof and respectively connected to the upper terminal slat of said upper section and to the lower terminal slat of said lower section for independently raising and lowering said sections, and slat tilting means carried by said frame adjacent the mid-height location of the latter and connected respectively to the lower terminal slat of said upper section and the upper terminal slat of said lower section for independently tilting the slats of said sections.

3. A Venetian blind assembly comprising a rectangular frame adapted to fit into a window opening, an upper and a lower blind section disposed in said frame respectively above and below the mid-height location of the latter and effective when extended to completely cover the area within said frame, each of said sections having an upper and a lower terminal slat, a plurality of intermediate slats disposed between said terminal slats and web ladders extending between said terminal slats and engaging said intermediate slats to hold said slats in operative assembly and tilt the intermediate slats upon tilting of the terminal slats when the blinds are extended, means pivotally connecting the lower terminal slat of said upper section and the upper terminal slat of said lower section to said frame with said lower and upper terminal slats extending transversely of the frame at the mid-height location of the latter and adjacent to each other, a plate extending transversely of the

frame at the mid-height location thereof and covering the edges of the pivotally mounted terminal slats, lifting cords supported on said frame at the upper end and at the mid-height location thereof and respectively connected to the upper terminal slat of said upper section and to the lower terminal slat of said lower section for independently raising and lowering said sections, slat tilting means carried by said frame adjacent the mid-height location of the latter and connected respectively to the lower terminal slat of said upper section and the upper terminal slat of said lower section for independently tilting the slats of said sections, and guide means for said upper section comprising cords extending between the lower terminal slat of said upper section and the top of said frame at respectively opposite sides of the latter and slidably engaging the ends of the intermediate slats of said upper section, and a spring connecting the ends of said cords at the top of said frame to maintain said cords under tension.
